[57] ABSTRACT

Certain bis(4-quinazolinyl) piperazines, e.g., 1,4-bis(6,7-dimethoxy-4-quinazolinyl)piperazine, are useful as anti-arrhythmic agents.

6 Claims, No Drawings

**METHOD FOR TREATING ARRHYTHMIA BY
USING 1,4-BIS(4 QUINAZOLINYL) PIPERAZINES**

This application is a continuation-in-part of copending U.S. Pat. Application, Ser. No. 241,408 filed Apr. 5, 1972 now abandoned.

This invention relates to the pharmaceutical activity of bis(4-quinazolinyl)piperazine derivatives. More particularly, this invention concerns the use of 1,4-bis(4-quinazolinyl) piperazines in the treatment of arrhythmia in mammals. The invention also relates to pharmaceutical compositions containing the above compounds as an active ingredient thereof.

The active agents with which this invention is concerned may be represented by the following structural formula:

where R₁ and R₂ each independently represent hydrogen or lower alkoxy i.e., alkoxy having 1 to 4 carbon atoms, e.g., methoxy, ethoxy, isopropoxy and the like, or a pharmaceutically acceptable acid addition salt thereof.

The preferred compound of formula (I) is the compound in which R₁ and R₂ are both methoxy, namely 1,4-bis (6,7-dimethoxy-4-quinazolinyl)piperazine.

The compounds of formula (I) above are known and may be prepared according to methods disclosed in the literature from known materials, for example as described in Example XIV of U.S. Pat. No. 3,594,480. The present invention contemplates only the novel use of such compounds in pharmaceutical applications, in particular in the treatment of arrhythmia.

As indicated above, the compounds of formula (I) are useful in animals as anti-arrhythmic agents as indicated by polygraph recordings on anesthetized dogs given 10 micrograms per kilogram of ouabain every 10 minutes until the appearance of constantly-occurring ventricular ectopic beats following which 0.1 to 10 milligrams per kilogram of the test compound is administered intravenously every two minutes until the arrhythmia reverts to sinus rhythm. The dog is anesthetized with 30 mg/kg i.v., of sodium pentobarbital and the polygraph recordings are made with a lead II electrocardiogram using pressure transducers connected to the cannulated femoral artery.

For such usage, the compounds may be administered orally or parenterally as such or admixed with conventional pharmaceutical carriers. They may be administered in such forms as tablets, dispersible powders, granules, capsules, syrups and elixirs and parenterally as solutions, suspensions, dispersions, emulsions and the like, e.g. a sterile injectable aqueous solution. The compositions may contain one or more conventional

adjuvants, such as sweetening agents, flavoring agents, coloring agents and preserving agents, in order to provide an elegant and palatable preparation. Tablets may contain the active ingredient in admixture with conventional pharmaceutically acceptable excipients, e.g., inert diluents, such as calcium carbonate, sodium carbonate, lactose and talc, granulating and disintegrating agents, e.g., starch and alginic acid, binding agents, e.g., starch, gelatin and acacia, and lubricating agents, e.g., magnesium stearate, stearic acid and talc. The tablets may be uncoated or coated by known techniques to delay disintegration and absorption in the gastro intestinal tract and thereby provide a sustained action over a longer period. Similarly, oral liquids, e.g., suspensions may contain the active ingredient in admixture with any of the conventional excipients utilized for the preparation of such compositions, e.g., suspending agents (methylcellulose, tragacanth and sodium alginate) wetting agents (lecithin, polyoxyethylene stearate and polyoxy-ethylene sorbitan mono-oleate) and preservatives (ethyl-o-hydroxybenzoate). Capsules may contain the active ingredient alone or admixed with an inert solid diluent, e.g., calcium carbonate, calcium phosphate and kaolin. The injectable compositions are formulated as known in the art. These pharmaceutical preparations may contain up to about 90 percent of the active ingredient in combination with the carrier or adjuvant.

Furthermore, the compounds of formula (I) may be similarly administered in the form of their non-toxic pharmaceutically acceptable acid addition salts. Such salts possess the same order of activity as the free base, are readily prepared by reacting the base with an appropriate acid and, accordingly, are included within the scope of the invention. Representative of such salts are the mineral acid salts, such as the hydrochloride, hydrobromide, sulfate, phosphate and the like and the organic acid salts, such as the succinate, benzoate, acetate, p-toluenesulfonate, benzene-sulfonate, maleate, malate, tartrate, methanesulfonate, cyclohexylsulfonate and the like.

The anti-arrhythmic effective dosage of the compounds of formula (I) employed in the alleviation of arrhythmia may vary depending on the particular compound employed and the severity of the condition being treated. However, in general, satisfactory results are obtained when the compounds of formula (I) are administered at a daily dosage of from about 3 milligrams to about 300 milligrams per kilogram of animal body weight, preferably given in divided doses two to four times a day, or in sustained release form. For most large mammals, the total daily dosage is from about 200 milligrams to about 3000 milligrams. Dosage forms suitable for internal use comprise from about 50 to about 1500 milligrams of the active compound in intimate admixture with a solid or liquid pharmaceutically acceptable carrier or diluent.

The preferred pharmaceutical compositions from the standpoint of preparation and ease of administration are solid compositions, particularly hardfilled capsules and tablets containing from about 100 to 250 milligrams of the active ingredient.

EXAMPLES 1 AND 2

65 Tablets and Capsules Suitable For Oral Administration

Tablets and capsules containing the ingredients indicated below may be prepared by conventional tech-

niques and are useful in treating arrhythmia at a dose of one tablet or capsule 2 to 4 times a day.

Ingredient	Weight (mg)	
	tablet	capsule
1,4-bis(6,7-dimethoxy-4-quinazolinyl) piperazine	150	150
tragacanth	10	—
lactose	297.5	150
corn starch	25	—
talcum	15	—
magnesium stearate	2.5	—
Total	500 mg.	300 mg.

In a similar manner, tablets and capsules may be prepared using 1,4-bis(4-quinazolinyl)piperazine or 1,4-bis(7methoxy-4-quinazolinyl)-piperazine as the active ingredient in place of the 1,4-bis(6,7-dimethoxy-4-quinazolinyl)piperazine above.

EXAMPLES 3 AND 4

Sterile Suspension for Injection and Oral Liquid Suspension

The following pharmaceutical compositions are formulated with the indicated amount of the active agent using conventional techniques. The injectable suspension and the oral liquid suspension represent formulations useful as unit doses and may be administered in the treatment of arrhythmia. The injectable suspension is suitable for administration once or twice a day whereas the oral liquid suspension is suitable administered 2 to 4 times per day for this purpose.

What is claimed is:

1. A method for treating arrhythmia, which comprises administering to a mammal in need of said treatment an anti-arrhythmic effective amount of a compound of the formula:

15

where R₁ and R₂ each independently represent hydrogen or lower alkoxy or a pharmaceutically acceptable acid addition salt thereof.

2. A method according to claim 1 wherein the compound is administered at a daily dosage of from about 200 milligrams to about 3000 milligrams.

3. A method according to claim 1 where in the compound is administered in a unit dosage form comprising said compound to the extent of from about 50 milligrams to about 1500 milligrams per unit dosage.

4. A method according to claim 1 in which the compound is 1,4-bis(6,7-dimethoxy-4-quinazolinyl)pipa-

Ingredients	Weight (mg)	
	injectable suspension	liquid suspension
1,4-bis(6,7-dimethoxy-4-quinazolinyl)piperazine	200	200
sodium carboxy methyl cellulose U.S.P.	1.25	12.5
methyl cellulose	0.4	—
polyvinylpyrrolidone	5	—
lecithin	3	—
benzyl alcohol	0.01	—
magnesium aluminum silicate	—	47.5
flavor	—	q.s.
color	—	q.s.
methyl paraben, U.S.P.	—	4.5
propyl paraben, U.S.P.	—	1.0
polysorbate 80 (e.g. Tween 80), USP	—	5
sorbitol solution, 70%, USP	—	2,500
buffer agent to adjust pH for desired stability	q.s. for injection, q.s. to 1 ml.	q.s. to 5 ml.
water		

In a similar manner, injectable suspensions and liquid suspension may be prepared using 1,4-bis(4-quinazolinyl)piperazine or 1,4-bis(7-methoxy-4-quinazolinyl)piperazine as the active ingredient in place of the 1,4-bis (6,7-dimethoxy-4-quinazolinyl)piperazine above.

55 zine.

5. A method according to claim 1 in which the compound is 1,4-bis(4-quinazolinyl)piperazine.

6. A method according to claim 1 in which the compound is 1,4-bis(7-methoxy-4-quinazolinyl)piperazine.
